UNITED STATES PATENT OFFICE.

GEORGE E. CURTISS, OF NEW BRITAIN, CONNECTICUT.

DESIGN FOR A TOASTER-FRAME.

47,394.

Specification for Design.

Patented June 1, 1915.

Application filed April 17, 1915. Serial No. 22,191. Term of patent 14 years.

To all whom it may concern:

Be it known that I, GEORGE E. CURTISS, a citizen of the United States, and a resident of New Britain, county of Hartford, State of Connecticut, have invented a new, original, and ornamental Design for a Toaster-Frame, of which the following is a specification, reference being had to the accompanying drawing, forming part hereof.

The drawing is a perspective view of a toaster frame embodying my invention.

I claim:

The ornamental design for a toaster frame as shown.

GEORGE E. CURTISS.

Witnesses:

M. E. HATTON,
J. HAROLD JOHNSON.
